US0D1086554S

(12) **United States Design Patent** (10) Patent No.: **US D1,086,554 S**
(45) Date of Patent: ** Jul. 29, 2025

(54) **TERPENE PRESERVATION UNIT**

(71) Applicants: **Charles Michael Scudder**,
Westminster, CO (US); **Christopher Heck**, Jacksonville, FL (US)

(72) Inventors: **Charles Michael Scudder**,
Westminster, CO (US); **Christopher Heck**, Jacksonville, FL (US)

(**) Term: **15 Years**

(21) Appl. No.: **29/989,278**

(22) Filed: **Feb. 11, 2025**

Related U.S. Application Data

(63) Continuation of application No. 18/586,068, filed on Feb. 23, 2024, now Pat. No. 12,221,264.

(51) **LOC (15) Cl.** **27-06**

(52) **U.S. Cl.**
